UNITED STATES PATENT OFFICE.

GUSTAVUS A. MONTGOMERY, OF TITUSVILLE, PENNSYLVANIA, ASSIGNOR TO TITUSVILLE FORGE COMPANY, OF TITUSVILLE, PENNSYLVANIA, A CORPORATION OF MARYLAND.

ELEVATOR FOR WELL CASINGS.

Application filed February 25, 1924. Serial No. 694,852.

This invention relates to improvements in elevators of the type employed in connection with oil or gas well drilling apparatus for lowering and raising the pipe or casing into 5 and out of the well.

One of the objects of the invention is to provide a semi-automatic casing elevator of this character in which the gripping jaws or slips are adjustable radially into and out of 10 engagement with the casing.

Another object of the invention is to provide novel means for controlling the expanding and contracting movements of the slips.

15 A further object is to provide means for yieldingly resisting movement of the slips out of their open or expanded position.

A still further object of the invention is to provide an elevator whose parts are so constructed and arranged that the same is 20 adapted for use with casings made with or without stop collars or shoulders.

In the accompanying drawings:

Figure 1 is a fragmentary side elevation 25 of the elevator, the bail being shown partly in section. Figure 2 is an enlarged central vertical section of the elevator, taken on line 2—2, Fig. 4, showing the slips in their contracted position about the casing. Figure 3 is a view similar to Fig. 2, showing the slips 30 in their expanded or released position. Figure 4 is a top plan view of the elevator with the top cap removed. Figure 5 is a vertical section on line 5—5, Fig. 4, the slips being 35 shown in their elevated or expanded position. Figure 6 is an enlarged horizontal section on line 6—6, Fig. 5. Figure 7 is a horizontal section on line 7—7, Fig. 2. Figure 8 is an enlarged perspective view of one 40 of the slips. Figure 9 is a similar view of the suspension or cam ring. Figure 10 is a fragmentary vertical section of a modified construction for guiding the slips in the tool-body. Figure 11 is a perspective view 45 of one of the slips employed with such modification. Figure 12 is a vertical section of a modified form of the improvement taken in the plane of line 12—12, Fig. 14. Figure 13 is a similar view taken on line 13—13, Fig. 50 14. Figure 14 is a plan view of this modification. Figure 15 is a horizontal section on line 15—15, Fig. 12. Figure 16 is an enlarged vertical section on line 16—16, Fig.

14. Figure 17 is a fragmentary sectional view, similar to Fig. 12, showing the slips 55 in their elevated or expanded position. Figure 18 is a sectional elevation taken in the plane of line 18—18, Fig. 17. Figure 19 is a fragmentary perspective view of one of the slips employed in connection with this 60 modified form of the improvement.

Similar characters of reference indicate corresponding parts throughout the several views.

In the preferred embodiment of the invention shown in Figs. 1—9, inclusive, the same comprises a substantially cylindrical body or suspension member 20 provided with a bore shaped to form conical seats or bearing openings 21 arranged in axial alignment one above the other lengthwise of the body and forming between them an annular downwardly-facing shoulder 22. The upper and lower ends of this body are provided with externally-threaded necks 23, 24, for 75 receiving caps 25, 26, respectively, having alining openings 27 therein through which the pipe or casing 28 extends. At its diametrically opposite sides the body has trunnions or pins 29 to which the lower ends of 80 links or bail-members 30 are connected, while their upper ends are adapted to be removably connected with the customary hook 31 attached to the derrick line.

Seated in the tapered openings of the body 85 20 is a pipe-gripping device preferably consisting of a plurality of slips or jaws 32 which are arranged in spaced relation in an annular series, and which are adapted for movement as a unit into and out of operative engagement with the casing. These slips are guided for vertical movement in the body-openings, and for this purpose each is preferably provided on its outer side with a dove-tail tongue 33 arranged to engage a 90 corresponding groove 34 in the walls of such openings. As shown in Figs. 2, 3, 6 and 8, these slips are of uniform width, their outer sides being stepped and tapered to correspond to the conical body openings 21. Between the upper and lower stepped outer bearing faces of each slip is formed an upwardly-facing shoulder 35 which is adapted 95 to engage the corresponding annular shoulder 22 of the body for limiting the upward movement of the slip relative to the latter, 100 105

the downward movement of the slips in the body being limited by the conical construction of the body-openings. The inner or gripping face of each slip is provided with 5 threads or wickers 36 to prevent the casing from slipping downwardly relatively to the body. By constructing the elevator body and the slips in this manner, the latter, upon moving up or down as a unit in the tapered 10 body-openings, are caused to be released or brought into gripping engagement with the pipe casing.

The slips are preferably connected as a unit and suspended so that they are retained 15 constantly in horizontal alignment and at the same time self-centering. For this purpose, they are carried by a collector ring or suspension member 37 provided in its periphery with a plurality of radial notches 20 or recesses 38 which correspond in number to the slips. Bolts or similar fastenings 39 connect these slips with the collector ring, whereby the slips are held against vertical displacement relative to the ring but are 25 capable of independent movement radially thereof to effect the expansion and contraction of the gripping device into and out of engagement with the casing.

Means are provided for effecting the uniform lowering and raising movement of the slips to bring them into and out of gripping 30 engagement with the casing. As shown in Figs. 2, 3, 5, 7 and 9, these means are preferably constructed as follows:

35 Disposed vertically in the spaces between the several slips are upright coil springs 40 which tend constantly to elevate the slips to the position shown in Figs. 3 and 5, in which position the slips are expanded and 40 free from engagement with the casing. To prevent the springs from buckling, they may be arranged in semi-circular grooves 41 formed in the tapered openings of the elevator-body, as shown in Fig. 6. The lower 45 ends of these springs bear against an annular seat or shoulder 42 formed on the lower cap 26, while their upper ends bear directly against the underside of the slip supporting ring 37. To effect the lowering 50 movement of the slips in the body-openings for the purpose of bringing them into gripping engagement with the casing, the upper cap 25 is adapted to co-operate with the slip supporting ring to force the slips downwardly as a unit when the cap is turned in one 55 direction, while when the cap is turned in the opposite direction, the springs 40 automatically cause the slips to be raised to their released position. To this end, the upper 60 cap 25 is provided on its inner wall with a plurality of downwardly-facing segmental cam portions 43 which are adapted to engage corresponding cam portions 44 carried by the collector ring. In the drawings, two sets of 65 cam portions are shown, but it will be under-

stood that any number may be employed, if desired. The effective faces of these cam portions are such that only a fractional turn of the cap is necessary to effect the maximum vertical movement of the slip relative to the 70 elevator body. As shown in Fig. 2, the opposing faces of the cam portions of the cap and collector-ring, respectively, are always in engagement with one another during the effective turning movement of the cap. 75

In assembling the slips within the body-bore, the upper and lower caps 25, 26, are removed, the slips 32 are inserted into said bore through the bottom thereof and connected with the collector-ring 37 by the bolts 80 39, the springs 40 are placed in their grooves, the caps are applied to the threaded necks of the tool-body, and the elevator is then ready for use, the upper cap being turned to bring the companion cam portions 43, 44, 85 into the position shown in Fig. 3, wherein the slips are in their elevated and expanded position to enable the elevator to be slipped over the casing.

In the construction of the elevator thus far described, the same is particularly intended for use with casings free from tool joints having externally projecting collars or shoulders. This elevator is so constructed, however, that it lends itself for 90 use with casings employing such stop-collars. For this purpose, reference being had to Fig. 5, the lower cap 26 is provided with an upwardly-opening socket or recess 45 for receiving a spacing ring or collar 46 which 100 serves to hold the slips in an elevated position against downward displacement and out of gripping engagement with the casing, the shoulder or collar 47 of the latter engaging the tops of the slips. 105

The operation of the device is as follows:

In applying the elevator to the casing, assuming the slips to be in their elevated or expanded position shown in Fig. 3, it is only necessary to turn the upper cap 25 a 110 fraction of a revolution to force the slips downwardly and inwardly into gripping engagement with the casing, as shown in Fig. 2, the wickers on the inner side of the slip preventing downward displacement of the casing relative thereto. When it is desired to disengage the casing from the elevator, the upper cap is turned in the reverse direction, causing the springs to automatically elevate the slips to their initial position. 115

Instead of guiding the slips in the body-bore by means of dovetail tongues and grooves, they may be suspended in the manner shown in Figs. 10 and 11. In this case, 125 each slip 48 is provided with an upright guide post or pin 49 rising from its offset portion 50 and arranged to engage a corresponding guideway or opening 51 in the elevator body. 130

In the modified construction of the elevator shown in Figs. 12-19, inclusive, means for effecting the lowering and raising movements of the slips to cause a corresponding contraction and expansion thereof relative to the casing are preferably constructed as follows:

52 indicates a collector-ring which is provided with an annular series of depending bolts or fastenings 53 held against vertical movement relative to said ring and terminating at their lower ends a suitable distance below the latter in segmental heads 54 from which the slips 55 are suspended. Near 10 their upper ends the slips are provided in their opposite sides with horizontal grooves 56 which are adapted to slidably engage the opposing marginal edges of the segmental heads, the latter being arranged in the spaces 20 between the slips, as shown in Fig. 15. By this construction, as the slips are raised and lowered as a unit in the tapered body openings, the slips are capable of moving radially in and out relatively to the segmental supporting heads. As in the previously described construction, coil springs 57 bearing at one end against the lower cap 58 and at 25 their other ends against the segmental heads, serve to constantly urge the slips of the unit 30 upwardly in the elevator-body.

The slips are forced downwardly by means of a rotatable cap 59 applied to the upper end of the elevator body and provided with alternately-arranged radial recesses 60 and 35 projections 61 which are adapted to be brought into and out of register with the tops of the slips. The inner edges of the cap-projections are adapted to engage a cam portion or inclined face 62 formed at the 40 upper end of the outer wall of each slip, so that as the cap is turned in one direction or the other, the slips are forced downwardly or automatically moved upwardly by the springs 57. In the lowered or contracted 45 position of the slips shown in Figs. 12 and 13, the projections 61 of the cap overhang the tops of the slips, preventing the slips from upward displacement while in such 50 position. When it is desired to release the slips from gripping engagement with the casing, the cap 59 is turned sufficiently to bring its recesses into register with the tops 55 of the slips, thereby permitting the springs to automatically elevate the slips and release them from engagement with said casing. A suitable handle or knob 63 may be applied to this cap to conveniently turn it.

I claim as my invention:

1. An elevator of the character described, 60 comprising a body having a tapered opening, a gripping device mounted in said opening and including a plurality of pipe-engaging jaws movable both lengthwise and radially of the opening, and a rotatable member adjustable lengthwise of said body and

arranged to control the longitudinal movement of said jaws as a unit for effecting their expansion and contraction.

2. An elevator of the character described, 70 comprising a body having a tapered opening, a gripping device mounted in said opening and including a plurality of pipe-engaging jaws movable both lengthwise and radially of the opening, means for yieldingly moving said jaws longitudinally in one direction to effect their expansion, and a rotatable member adjustable lengthwise of said body for controlling the movement of said jaws as a unit in the opposite direction to effect their contraction.

3. An elevator of the character described, 80 comprising a body having a tapered opening, a supporting member, a plurality of pipe-engaging jaws connected to said supporting member for movement radially thereof, and a rotatable member adjustable lengthwise of said body and arranged to engage the jaw-supporting member for controlling the longitudinal movement of the 85 jaws in said body-opening.

4. An elevator of the character described, 90 comprising a body having a tapered opening, a supporting member, a plurality of pipe-engaging jaws connected to said supporting member for movement radially 95 thereof, yieldable means bearing against one side of the jaw-supporting member for elevating the jaws to their expanded position, and rotatable means adjustable lengthwise on said body and arranged to bear against the opposite side of the jaw-supporting member for lowering the jaws to their contracted position.

5. An elevator of the character described, 100 comprising a body having a tapered opening, a supporting member, a plurality of pipe-engaging jaws connected to said supporting member for movement radially 105 thereof, said jaws being arranged in an annular series and in spaced relation, springs disposed in the spaces between said jaws 110 and bearing against the underside of the jaw-supporting member for elevating the jaws to their expanded position, and means mounted on said body and arranged to bear 115 against the upperside of said supporting member for lowering the jaws to their contracted position.

6. An elevator of the character described, 120 comprising a body portion having a tapered opening, a plurality of pipe-engaging slips guided for longitudinal movement in said opening, a rigid suspension member connecting said slips as a unit for preventing their vertical displacement relative to one another, 125 said slips being movable radially of said suspension member, and rotatable means applied to said body-portion for movement lengthwise thereof and engaging said suspension member for controlling the move- 130

ment of the slips lengthwise in said opening, said rotatable means constituting an enclosure for the upper ends of the slips and the suspension member.

- 5 7. An elevator of the character described, comprising a body portion having a tapered opening, a plurality of pipe-engaging slips guided for longitudinal movement in said opening, a collector-ring applied to the upper ends of said slips for preventing their relative vertical displacement, headed fastenings connecting the collector-ring with the slips, said ring having radial notches engaging the shank portions of said fastenings for permitting radial movement of the slips relatively to said ring, and rotatable means applied to said body-portion above the collector ring for controlling the movement of said slips lengthwise in said body opening.
- 10 8. An elevator of the character described, comprising a body portion having a tapered opening, pipe-gripping means mounted in said opening to expand or contract, and rotatable means adjustable lengthwise on said body-portion for controlling the movement of said gripping means to its contracted position, both of said means being provided with complementary contacting portions for effecting the movement of the gripping means when said controlling means is actuated.

- 15 9. An elevator of the character described, comprising a body portion having a tapered opening, pipe-gripping means mounted in said opening to expand or contract, rotatable means adjustable lengthwise on said body-portion for controlling the movement of said gripping means to its contracted position, both of said means being provided with complementary contacting portions for effecting the movement of the gripping means when said rotatable means is actuated, and means for yieldingly moving said gripping means to its expanded position.

- 20 10. An elevator of the character described, comprising a body portion having a threaded-neck, a plurality of pipe-engaging slips guided for both lateral and longitudinal movement relative to said body portion, means tending constantly to move said slips in a direction to expand them, and a rotatable threaded cap applied to said threaded-neck for engagement with said slips for forcing them lengthwise of the body into their contracted position.

- 25 11. An elevator of the character described, comprising a body portion having a threaded-neck, a plurality of pipe-engaging slips guided for both lateral and longitudinal movement relative to said body portion, means tending constantly to move said slips in a direction to expand them, and means for moving said slips in the opposite direction to contract them including a rotatable

30 threaded cap applied to the threaded-neck of said body portion, said slips and said cap having complementary cam portions arranged for engagement with each other.

35 12. An elevator of the character described, comprising a body portion having a tapered opening, a plurality of pipe-engaging slips guided for longitudinal movement in said opening, a supporting member for said slips for preventing their vertical displacement relative to one another, means for yieldingly moving said slips to their elevated expanded position, and a cap rotatably mounted on said body portion for controlling the movement of the slips to their lowered contracted position, said cap being provided with a cam portion and said slip supporting member having a complementary cam portion.

40 13. An elevator of the character described, comprising a body portion having a tapered opening provided with substantially radial guide-grooves extending lengthwise thereof, and a gripping device arranged in said opening and including a plurality of slips having guides engaging said guide-grooves, and a rotatable member adjustable lengthwise of said body and arranged to control the longitudinal movement of said slips as a unit for effecting their expansion and contraction.

45 14. An elevator of the character described, comprising a body having tapered openings disposed one above the other in axial alignment and forming a downwardly-facing stop shoulder between them, a gripping device including slips arranged in said opening, each of said slips having upper and lower stepped exterior bearing faces forming an upwardly-facing shoulder between them and arranged to engage the downwardly-facing stop shoulder of said body-openings, and means for raising and lowering said gripping device in said opening to effect the expansion and contraction thereof.

50 15. An elevator of the character described, comprising a body portion having a tapered bore, a gripping device mounted in said bore and movable lengthwise thereof to expand and contract, caps applied to the upper and lower ends of said body portion and having openings therein in line with said bore, one of said caps engaging said gripping device to move it in one direction, and springs for moving the gripping device in the opposite direction, said springs bearing at one end against said other cap.

55 16. A slip for a pipe-gripping device, having its outer side provided with downwardly tapering bearing faces disposed one above another and an upwardly-facing stop shoulder formed between said faces, and dovetail tongues extending laterally from said bearing faces.

GUSTAVUS A. MONTGOMERY.
